UNITED STATES PATENT OFFICE.

SAMUEL H. THOMSON AND ROBERT H. HUMMERT, OF DAYTON, OHIO, ASSIGNEES TO
THE S. H. THOMSON MANUFACTURING COMPANY, OF DAYTON, OHIO.

SPOT LAMP FOR AUTOMOBILES AND THE LIKE.

Application filed September 22, 1921. Serial No. 502,451.

To all whom it may concern:

Be it known that we, SAMUEL H. THOMSON and ROBERT H. HUMMERT, citizens of the United States, residing at Dayton, in the county of Montgomery and State of Ohio, have invented certain new and useful Improvements in Spot Lamps for Automobiles and the like, of which the following is a specification, reference being had therein 10 to the accompanying drawings.

This invention relates to spot lamps for automobiles and the like, having particular reference to improvements in spot lamps of the type illustrated and described in United 15 States Patent No. 1,388,220—issued August 23, 1921.

The main feature of advantage in spot lamps of this character consists in their wide 20 range of adjustment,—the lamps being adjustable in both horizontal and vertical planes of rotation, or in any two given planes of rotation at right angles one to the other. Thus the range of light projection, by a 25 combination of the double adjustment, is practically universal,—that is to say the lamps can be adjusted to project the light at any desired angle.

The improvements of the present invention consist in providing improved mounting 30 brackets for the lamp fixture as a whole, the brackets being in two forms—for open and closed automobiles, respectively, and adapted in principle to standard automobiles of all makes; in single controlling means for adjusting the lamp in either plane of its movement; in positive means for automatically 35 securing the lamp in any adjusted position; in means to effect neater connections of the wiring of the lamp and to avoid short-circuiting of the connections; in improved 40 means for adjusting the focus of the lamp; means for eliminating play, or lost motion in the mechanism; and, generally, in refinements and simplification of the lamp fixture 45 as a whole to better adapt it for manufacturing, for more convenient mounting of the lamp on automobiles of different makes, and for ease of adjustment of the lamp,—the improvements being illustrated in the accompanying drawings, described in detail in the 50 specification, and defined in the appended claims.

In the drawings:

Fig. 1 illustrates the lamp fixture as 55 mounted on a closed automobile;

Fig. 2 illustrates the lamp fixture as mounted on an open automobile;

Fig. 3 is a view in longitudinal section of the lamp fixture removed from the mounting bracket;

Fig. 4 is a detail view of the mounting bracket for open automobiles;

Fig. 5 is a detail in two views of the mounting bracket for closed automobiles;

Fig. 6 is a detail view in cross section on 65 the line 6—6 of Fig. 3;

Fig. 7 is a detail view in cross section on the line 7—7 of Fig. 3, and

Fig. 8 is a detail view in cross section of a portion of the mounting bracket shown in 70 Fig. 4.

As here shown, the main features of the spot lamp fixture consist of the lamp —1 which may be of any suitable type,—the common commercial types of spot lamps being adaptable for use with the fixture; a lamp supporting base —2; lamp adjusting head —3; lamp fixture extension —4; lamp adjusting handle —5; lamp fixture mounting bracket —6, and lamp wiring —7.

The lamp base —2 is provided with an externally threaded stem —8 over which the internally threaded socket 9 of the lamp fits. The lamp bulb —10, as here shown, is provided with a hollow stem —11 which projects into the lamp base and is adapted to have longitudinal movement therein to adjust the focus of the light. To this end the stem —11 is provided with a rack —12 formed on the under side thereof, and a pinion gear —13 mounted in base —2 and having one of its ends exposed and screw slotted, as at —14, meshes with the rack and serves as a means for adjusting the focus of the lamp. A set screw —15 serves to lock 95 pinion —13 and to hold the lamp bulb in adjusted position,—a pin or key —16 secured in stem —11 and cooperating with a key slot —17 formed internally in the upper wall of base —2, serves to prevent rotation 100 of the bulb and thus to maintain normal relation between rack —12 and gear —13.

The lamp base —2 is cored out, as illustrated at —18, to provide ample clearance for the wiring —7 of the lamp, and is provided with a hollow stem —19 which forms the axis for horizontal adjustment of the lamp,—the stem extending through the adjusting head —3 and opening into space —18, thus the wires, which are connected 110

to the lamp bulb in the usual manner by a bayonet lock connection —20, are conducted through stem —19 and thence to the source of electrical current for the lamp, as the 5 battery of the automobile. The arrangement of the wiring, as here shown, effects a neat connection to the lamp and minimizes the possibility of short-circuiting of the connections by the accumulation of moisture 10 in the exposed lamp base and lamp adjusting head, the construction being practically moisture-proof and also well adapted to exclude dust or grit from the internal parts of the mechanism.

15 Stem —19 of the lamp base is mounted in a yoke bearing —21 which also serves to form three walls of the adjusting head casing, the open end and sides of the yoke being closed by a cover cap —22 which fits in shallow ledges —23 formed in the inner edges 20 of the yoke bearing arms —21, thus the outer surface of cap —22 will be flush with the outer edges of arms —21 to effect neat construction, the cover cap being secured to the yoke by means of opposite screws —24. Adjacent its lower bearing, stem —19 has a bevel gear —25 secured thereto which meshes with a bevel gear —26 on the end of a shaft —27 of the lamp fixture extension —4. A spring washer —28 is interposed between gear —25 and lower bearing —21, thus serving to compensate for wear and to take up any lost motion of the parts of mechanism in the lamp adjusting head.

35 The lamp fixture extension —4 consists of an outer tube —29 which is adapted to be rigidly clamped in the lamp mounting bracket —6, the tube projecting slightly at 40 its outer end, as at —31, into the hub of yoke —21, the yoke being free to rotate about the end of the tube. At its inner end tube —29 has a ratchet gear —32 secured thereto for a purpose which will presently 45 be described. Tube —29 is arranged telescopically over a tube —30 which in turn is arranged telescopically over the shaft —27, bushings —a, b, c, d— being disposed between shaft —27 and tube —30, and between tube —30 and tube —29, adjacent 50 their ends to compensate for the differences in their respective diameters and to provide suitable bearing relations therebetween.

55 Tube —30 has yoke —21 secured to its outer end and a sleeve —33 secured to its inner end by a set screw —34, the end of the sleeve toward tubes —29 and —30 being counter-bored to receive gear —32 to form a 60 neat enclosure therefor. Pivoted on top of sleeve —33 is a latch —35 provided with a finger piece —36 and adapted to cooperate with gear —32 to interlock tubes —29 and —30, and to release tube —30 from tube —29 to permit of free movement thereof 65 according to the adjustment that is desired

to be made of the lamp. The opposite end of sleeve —33 is serrated, as at —37 to form a clutch or ratchet relation with a sleeve —38 upon which the lamp adjusting handle —39 is mounted, the inner end of sleeve —38 being serrated, in like manner, as at —37, to form the clutch connection with sleeve —33. Sleeve —38 is splined on shaft —27 by means of a key —40, and is retained on the shaft by a stud cap screw —41, the outer end of the sleeve being counter-bored to receive a compression spring —42 interposed between the head of screw —41 and the bottom of the counter-bore. Thus the adjusting handle may be moved outwardly 80 on shaft —27, from the position shown in Fig. 3, to disengage the handle from sleeve —33 and to permit rotative movement of shaft —27, independently of tube —30, to adjust the lamp in its horizontal plane of 85 movement, adjustment of the lamp in a vertical plane being effected, upon releasing of latch —35, by turning of handle —39, shaft —27 and tube —30 being then interlocked and turning one with the other. 90

The lamp fixture mounting bracket for an open automobile is best shown in detail Figs. 4 and 8, and the mounting bracket for closed automobiles in detail Fig. 5, the object sought in the design of the brackets being 95 to provide brackets adapted for mounting the spot lights on open and closed automobiles of different makes. The bracket illustrated in detail in Figs. 4 and 8, consists of opposite clamp jaw members —43 and —44, 100 joined one to the other by clamp bolts —45 which pass freely through apertures —46 in clamp member —44 and are threaded into apertures —47 in member —43 which is further provided with fulcrum studs —48 which 105 act as a stop for the free end of clamp member —44 as the bolts —45 are drawn down to fasten the clamp on the windshield frame —49. Clamp member —43 is further provided with a threaded stem —50 which is 110 adapted to fit the transverse aperture of a longitudinally-slotted sleeve —51— shown in detail in Fig. 8—in which the outer tube —29 of the lamp fixture extension —4 is mounted, the sleeve being firmly secured to 115 tube —29 and to clamp member —43 by a clamp nut —52 turned down on the end of stem —50. By this arrangement both longitudinal and pivotal adjustments can be made 120 of the lamp fixture extension, as may be desired, to adapt the mounting to the particular automobile on which it is to be used.

The lamp bracket for closed automobiles, illustrated in detail in Fig. 5, consists of a sleeve —53 which is adapted to receive tube —29 of the lamp fixture extension, the bracket having an arm —54 for fastening the bracket to the windshield casing, the sleeve and bracket being internally slotted and fitted with a clamp screw —55 cooperat- 125 130

ing with the slot to firmly secure tube —29 in the sleeve. As illustrated in broken detail in Fig. 1 of the drawings, tube —29 extends through the windshield casing with the sleeve —53 butted against the casing on the inside, and an escutcheon —56 fits over the tube and is secured to the casing on the outside, a dust and moisture excluding gasket —57 being interposed between the es-
10 cutcheon and casing.

From the foregoing detailed description and the illustrations shown in the drawings, the construction and use of our improved spot lamp will be readily understood. It
15 will be seen that upon outward pressure being exerted on adjusting handle —39, to release the handle from sleeve —33, shaft —27 will be free to be rotated in either direction, upon turning of the handle, to adjust the
20 lamp angularly in a horizontal plane, or in a plane parallel to the axis of the shaft, if the lamp fixture should be set at an angle on stem —50 of the mounting bracket and, upon releasing of the handle, the lamp will be
25 firmly held in any such position of adjustment by the serrations —37; and upon releasing of latch —35 with gear —32, the adjusting handle being then in engagement with sleeve —33, tube —30 and shaft —27
30 will be free to rotate in unison one with the other to effect adjustment of the lamp in a vertical plane, or in a plane at right angles to the axis of the tube and shaft, irrespective of the position of the lamp in its other plane
35 of adjustment,—the lamp being held in any position of adjustment in the right angle plane by reengagement of latch —35 with gear —32. Thus it will be seen that the range
40 of angular adjustment of the lamp by a combination of adjustments in the two planes is practically universal, and that the adjustments can be made quickly and easily by the single controlling handle.

Having described our invention, we claim:

- 45 1. In a spot lamp fixture, the combination with a mounting bracket, of a tubular member adjustably mounted in said bracket and having a peripheral locking member fixed to an end thereof, a rotatable tube in said member having a sleeve secured to an end thereof, a latch mounted in said sleeve and adapted to effect locking engagement with said locking member to interlock the tube with said tubular member, a rotatable shaft in said tube
50 having an adjusting handle secured thereto and normally in yielding locking engagement with said sleeve, a spot lamp connected to said tube and shaft at the opposite ends thereof and adapted to be adjusted rotatably
55 in one plane by operation of said handle upon disengaging said latch from said locking member and in another plane of rotation upon disengaging the adjusting handle from said sleeve.

- 60 2. In a spot lamp fixture, the combination

with a mounting bracket, of a fixture extension adjustably mounted in said bracket comprising three longitudinal members arranged concentrically one with another, the outer of said members being normally fixed 70 in said bracket and all of said members being normally interlocked one with another, means including a single operating handle to disengage one member from another, a spot lamp connected to said extension and 75 adapted to be adjusted in a plurality of planes to a plurality of predetermined positions, and means coacting with the operating handle to lock said lamp in any one of said positions.

3. In a spot lamp fixture, the combination with a mounting bracket, of a fixture extension adjustable rotatably and longitudinally in said bracket comprising three longitudinal members arranged concentrically one 80 with another, the outer of said members being normally fixed in said bracket and all of said members being normally interlocked one with another, a spot lamp mounted on one end of said extension and adapted for 85 adjustment rotatably in a plurality of planes, a sleeve having a serrated end mounted on the intermediate of said members at its opposite end and having a finger latch for effecting said interlocking relation with 90 the outer member, an adjusting handle mounted yieldingly on the inner of said members adjacent said latch and having a serration adapted normally to coact with the serration of said sleeve to interlock the 95 inner member with the intermediate member, whereby adjustments of said lamp can be effected in either of said planes.

4. In a spot lamp fixture, the combination with a mounting bracket, of a tubular member normally fixed in said bracket and having secured to one end thereof a locking member provided with means for effecting locking engagements with coacting parts in a plurality of circumferentially arranged 100 positions, a rotatable tube in said member having a member adapted to coact with said locking member to effect said locking engagements thus to retain the rotatable tube in adjusted relation relative to said tubular 110 member, a rotatable shaft in said tube, a spot lamp connected to said tube and shaft at one of the ends thereof, and an adjusting handle adapted to coact with said tube and shaft at the opposite ends thereof to 120 effect adjustment of the lamp to a plurality of positions in different planes.

5. In a spot lamp fixture, in combination with a fixture extension, of a mounting bracket comprising opposite clamp members 125 for securing said bracket to a support, one of said members having formed integrally therewith a threaded stem extending outwardly of said bracket, a split sleeve adapted to be pivotally mounted on said stem and 130

- to support said fixture extension, and a clamp nut on said stem to secure said sleeve to said fixture extension and bracket.
6. In a spot lamp fixture, in combination with a mounting bracket comprising opposite clamp members for securing the bracket to a support, one of said members having formed integrally therewith a threaded stem extending outwardly of the bracket, and a split sleeve adapted to be pivotally mounted on said stem, of a fixture extension mounted for longitudinal adjustment in said sleeve, and a clamp nut on said stem to secure said sleeve to said fixture extension and bracket.
7. In a spot lamp fixture, the combination with a fixture extension, of a spot lamp mounted on an end thereof, said mounting comprising a rotatable yoked bearing, a low stem constituting part of a lamp adjusting head operable in said bearing, a cover enclosing said bearing and stem, and the wiring for the lamp encased in the lamp head and said stem.
8. In a lamp mounting fixture, the combination with a lamp adjusting head comprising a yoke bearing, the arms and base of the yoke serving to form the walls for the adjusting head closure on three sides thereof, of a ledge formed along the inner edges of said arms and base, and a cover cap secured in said ledge over the open end and sides of the yoke and flush with the outer surface thereof.
9. In testimony whereof, we affix our signatures.

SAMUEL H. THOMSON.
ROBERT H. HUMMERT.
